US00D754534S

(12) **United States Design Patent**
Sanfilippo et al.

(10) **Patent No.:** **US D754,534 S**
(45) **Date of Patent:** **** Apr. 26, 2016**

(54) **PACKAGE**

- (71) Applicant: **CLEAR LAM PACKAGING, INC.**,
Elk Grove Village, IL (US)
- (72) Inventors: **James J. Sanfilippo**, Barrington Hills,
IL (US); **Eric Feld**, Aurora, IL (US);
Michael Butkus, Bartlett, IL (US);
Michael Alianello, Buffalo Grove, IL
(US)

Primary Examiner — Susan Bennett Hattan

Assistant Examiner — Vy Koenig

(74) *Attorney, Agent, or Firm* — Marshall, Gerstein & Borun LLP

(57) **CLAIM**

The ornamental design for a package, as shown and described.

DESCRIPTION

FIG. 1 is a front, right-side, and top view of a package that has the design.

FIG. 2 is a front view of the package.

FIG. 3 is a right-side view of the package.

FIG. 4 is back view of the package.

FIG. 5 is a left-side view of the package.

FIG. 6 a top plan view of the package; and,

FIG. 7 is a front, right-side, and bottom view of the package.

1 Claim, 4 Drawing Sheets
